INCANDESCENT LAMP

Application filed May 10, 1930. Serial No. 451,458.

This invention relates to improvements in incandescent lamps and has for its primary object to provide an attachment for an incandescent lamp which is placed therein during the manufacturing of the same which will act to materially improve the dispersion of the light produced by the filament in the lamp thus improving the efficiency of the lamp generally.

10 Another object of the invention is to provide an improved incandescent lamp of the above described character which in addition to being more efficient than the ordinary type of lamp, may be produced at approximately 15 the same or a very little more than the cost of producing the ordinary lamp.

The invention will be best understood from a consideration of the following detailed description taken in connection with the accompanying drawings forming part of this specification, with the understanding, however, that the invention is not confined to any strict conformity with the showing of the drawings but may be changed or modified so long as 25 such changes or modifications mark no material departure from the salient features of the invention as expressed in the appended claim.

In the drawings:
30 Figure 1 is a view in longitudinal section of an incandescent lamp constructed in accordance with our invention.

Figure 2 is a sectional view taken on the line 2-2 of Figure 1.
35 Referring more particularly to the drawings wherein like numerals of reference indicate corresponding parts throughout the several views, the numeral 1 indicates generally an incandescent lamp of one of a number of 40 various forms, the bulb or globe thereof being indicated by the numeral 2 and the base by the numeral 3.

Within the bulb 2 there extends longitudinally through the neck portion of the bulb 45 from the base 3 the usual glass filament supporting rod 4 the lower end of which is slightly enlarged as indicated at 5, in the usual manner, through which enlarged portion of the filament carrying wires 6 extend, emerging therefrom at the point where the rod 4

joins the base portion 5 to extend toward the forward end of the globe at opposite sides of the rod in the manner shown.

Upon the forward end of the rod 3 there is fixed a glass bulb 7 which, as shown, is substantially pear shaped or ovoid in outline, the smaller end being attached to the rod. 55

The interior surface of this ovoid bulb 7 is coated with suitable material to give the same a mirrored appearance from the exterior. While silvering of the interior surface is preferred it is, of course, to be understood that we do not wish to be limited in this respect for many other types of coating material may be effectively employed. 60

Surrounding the bulb 7 and in relatively close proximity to the surface thereof is the lamp filament 8 the ends of which are attached to the wires 6 in the usual manner and extending upwardly along the smaller end of the bulb 7 from the end of the rod 4 are the filament support bars 9. 65

From the foregoing it will be seen that the bars 9 which support the filament 8 form a cup into which the reduced or constricted end 70 of the bulb 7 extends and the filament is located a slight distance, preferably about one-eighth of an inch, inwardly from the center of the reflecting bulb 7. With this construction the light emitted by the filament 8 will be evenly dispersed in all directions radially from the bulb 7 by which the filament is surrounded. 75

Having thus described our invention, what we claim is:

80 In an incandescent lamp, including a globe, a base and a filament supporting rod within the globe and carried by the base; a transparent bulb of substantially pear-shape configuration secured at its smaller end to the free end of said rod, silvering material upon the inner face of said bulb, a plurality of wire bars secured to the bulb at the point of jointure of the same with the rod and extending forwardly in close, substantially 85 parallel relation along the tapered portion of the bulb, a filament wire suspended from the free ends of said bars and encircling the bulb inwardly of the widest portion thereof, and current carrying wires connected with 90 95 100

the filament, said filament being arranged in close proximity to the bulb.

In testimony whereof we hereunto affix our signatures.

5 JOHN W. GILLELAND.
CLINTON A. McHENRY.
HOMER G. KRUEGER.
